NONSLIP GARMENT CLIP

Otto Lawrenz, River Forest, Ill., assignor to Peerless Tool & Engineering Company, Chicago, Ill., a corporation of Illinois

Application May 28, 1949, Serial No. 95,990

2 Claims. (Cl. 24—81)

1

The present invention relates to improvements in garment clips, and more particularly to the types of clip which are adapted for use as men's collar bars or clips, tie clips, or bow tie clips or retainers.

Clips or bars of this type, in one popular form, comprise a pair of more or less resilient, opposed frictional retaining and gripping arms or levers which may be in the form of a pair of bars secured together at adjacent ends or at their center, depending upon whether one or two gripping jaws are to be provided.

In the use of such a garment clip, the margin of a collar or shirt front is forced edgewise between the spring jaws provided by the device and the spring jaws provide a clamping gripping action by which the clip is retained on the garment.

One of the principal disadvantages of this type of garment clip resides in the liability of the garment margin to which the clip is applied slipping out from between the jaws or the clip becoming dislodged from the margin in response to longitudinal force applied in some manner relatively between the garment margin and the clip.

It is therefore a principal object of the present invention to provide a spring jaw garment clip which is provided with novel means for substantially preventing accidental separation of the clip from the garment.

Another object of the invention is to provide a garment clip of the spring jaw type wherein novel means are provided which will permit easy and unrestrained application of the clip jaw to the margin of the garment by relative movement to force the garment margin between the jaws but then so gripping the garment margin that accidental withdrawal is substantially prevented.

Other objects, features and advantages of the present invention will be readily apparent from the following detailed description of a preferred embodiment thereof taken in conjunction with the accompanying drawings in which:

Figure 1 is an enlarged front elevational view of a garment clip in the form of a collar bar embodying the features of the present invention;

Figure 2 is a top plan view of the garment clip;

Figure 3 is a substantially enlarged fragmentary top plan view of one of the jaw portions of the garment clip; and

Figure 4 is another fragmentary plan view of the clip jaws as shown in Figure 3 but illustrating the same after application to the margin of a portion of a garment such as a collar.

2

Whereas the specific form of device illustrative of the present invention is shown in the drawing as a collar bar 10, it will be understood that the same general structure can also be used for a bow tie retaining bar or clip and that while a collar bar or bow tie clip has two oppositely directed identical collar-engaging jaw structures, a tie clip customarily has but one such jaw structure and the levers or lever portions comprising the jaw structure of such a tie clip are usually longer in order to accommodate the greater span that must be covered in a tie clip as compared to a collar bar. It will be readily appreciated that the same principles will apply to either of the several forms suggested although the specific illustration is of a collar bar, and it should therefore be understood that the term "garment clip" is to be understood throughout the specification and claims as generic to any particular practical form that the invention may take.

Having more specific reference, now, to the garment clip 10 in the form of a collar bar, it comprises a front jaw lever bar 11 and a rear jaw lever bar 12, the latter being preferably slightly shorter than the former. The bars are either or both but at least preferably the rear bar 12, relatively resiliently flexible and are secured together at their central portion in any suitable manner as by means of a securing ferrule 13. In the present instance each end portion of the rear jaw lever bar 12 is formed with a loop portion 14 which defines an eye 15 and with which the opposing end portion of the outer jaw lever bar 11 cooperates to provide a pair of jaws between which the margin of a collar 17 is adapted to be gripped. To facilitate the collar margin gripping action, the outer bar 11 has the outer end jaw portion thereof bowed, as indicated at 18. The bowed portion 18 provides a humped pad which is of a width and arc to extend into the eye 15 thereby dimpling the interposed collar margin 17 and in cooperation with the jaw 14 which is preferably bowed in opposition to the hump 18 retaining a fairly secure grip upon the collar margin. However, it has been found that this construction alone, is ineffective to retain the garment margin securely enough to prevent accidental withdrawal of the garment in response to separating forces, such as certain movements of the wearer which effect mutual separating tension upon the opposite wings of the collar.

According to the present invention operation 55 of the jaws 14 and 18 is substantially improved

for retaining the interposed garment margin by the provision of novel retaining means effective to resist withdrawal of the garment margin from between the jaws but permitting just as easy assembly of the clip on the garment margin as with a clip not so equipped. To this end, one of the jaws, herein the jaw 14 of the inner lever jaw bar 12, in each instance, is formed with a transverse series of retaining teeth 19 on the humped portion of the jaw and as best seen in Figure 1 comprising actually two sets of the teeth 19 which may be, though not necessarily, aligned on each side of the eye 15 in the jaw.

As best seen in Figures 3 and 4, the retaining teeth 19 are of generally saw toothed cross section and have cam surfaces 20 sloping toward the inside of the jaw assembly while the opposite or inner sides of the teeth have surfaces substantially radial to the arc of the jaw 14 so that the point of each tooth is directed generally inwardly of the jaw assembly. As a result, when the clip is applied to the collar margin 17, the edge of the collar cams against the cam surfaces 20 of the teeth, substantially as indicated in Figure 3 and slides past the teeth into the jaw, the bars 11 and 12 or perhaps merely the bar 12 yielding resiliently to receive the collar margin 17 therebetween.

After the collar margin 17 is engaged between the jaws as shown in Figure 4, the points of the teeth 19 tend to dig into the material of the collar wing margin substantially as shown and resist separation of the collar margin while clampingly engaged between the jaws 14 and 18. As a matter of fact the harder a separating pull is applied to relatively separate the clip and the collar wing, up to a certain extent, the more firmly will the teeth 19 grip the collar margin. Since there are a relatively large number of the teeth 19, the gripping action of the teeth is distributed over a substantial area of the collar margin and therefore damage by tearing or ripping is avoided.

In order to release the collar margin 17 the bars 11 and 12 of the clip are sprung apart, or at least the bar 12 is levered apart by springing the same resiliently as indicated in dash outline in Figure 4 and the collar margin can then be readily slipped out from the clip or the clip separated longitudinally from the collar margin.

By having the retaining teeth 19 formed on the opposite sides of the loop of the jaw 14 and normal to the axis of the outer bar 11, especially effective retention is afforded since by the dimpling inwardly pressing action of the curvate or humped jaw 18, substantially as shown in Figure 4, the inner ends of the teeth 19 are especially effective to engage with the back of the collar margin but without any mechanical direct action of the jaw 18 toward the teeth to cause cutting of the fabric of the collar interposed between the jaws. In other words, the teeth 19 can find anchorage behind or beside threads or fibers of the fabric of the collar and will not act to sever or damage the fibers as might be the case were the outer jaw to directly oppose the teeth and drive or bear resiliently and under spring tension to-

ward the teeth in direct opposition. Damage to the fabric of the collar is thus avoided even though the clip may be used repeatedly on the same collar and in approximately the same place on the collar, or other portion of the wearer's shirt as for example the shirt front where the clip comprises a tie clip.

I claim as my invention:

1. In a garment clip having a pair of opposed spring jaw members, one of said jaw members comprising a loop having an eye humped toward one side and the other of said jaw members comprising a bar formed with a gently humped portion extending generally from said one side into said eye, said jaw members being cooperatively related to receive a garment margin therebetween by relative movement longitudinally of the clip jaws and the garment margin, said looped jaw member having a series of retaining teeth thereon at the humped side of said eye and spaced from said humped bar jaw member, said teeth being located on both sides of said loop jaw member and cooperating to engage in the material of the interposed garment margin under the influence of said humped bar jaw member but without direct biting into the material because of the spaced relation of the adjacent ends of the teeth with respect to said humped bar jaw member.

2. In a non-slip garment clip adapted for engaging and retaining in place the adjacent ends of a collar, a rear bar of elongated form and having a loop of substantial width at each respective opposite end portion, said loop being humped forwardly with the tip portion of each loop angled generally rearwardly, transverse retaining teeth on the humped faces of the respective loops at opposite sides of the opening in the loop, a front bar having the end portions rearwardly humped complementary to the forward humps of the respective rear bar loops and normally extending with the humped portions thereof into the loops clear of any direct contact therewith and intermediate the toothed hump portions of the loops, the respective end portions of the front bar being angled away from the tip portions of the rear bar loops, and means securing said bars in assembly so that opposite aligned portions of a garment can be inserted between the humped loop and front bar portions to be retained by pressure of the bars engaging said retaining teeth against the back face areas of the garment portions.
